ATTORNEYS.

UNITED STATES PATENT OFFICE

158,666

GREETING CARD OR THE LIKE

Eugenie J. Jones, Webster Groves, Mo.

Application March 5, 1949, Serial No. 1,243

Term of patent 14 years

(Cl. D59—2)

To all whom it may concern:

Be it known that the undersigned, Eugenie J. Jones, a citizen of the United States, residing at Webster Groves, St. Louis County, Missouri, has invented a new, original, and ornamental Design for a Greeting Card or the like, of which the following is a specification, reference being had to the accompanying drawing, forming a part thereof.

The figure in the drawing shows a greeting card showing my new design.

The essential features of the design reside in the portions shown in full lines.

I claim:

The ornamental design for a greeting card or the like, substantially as shown and described.

EUGENIE J. JONES.
